(57) **CLAIM**

The ornamental design for the eyeglass frame, as shown and described.

DESCRIPTION

FIG. 1 is a front elevational view of the eyeglass frame showing my new design;

FIG. 2 is a rear elevational view thereof;

FIG. 3 is a left side elevational view thereof, the right side elevational view being the mirror image of the left side elevational view;

FIG. 4 is a top plan view thereof;

FIG. 5 is a bottom plan view thereof; and,

FIG. 6 is a perspective view taken from the front, top and left side of the eyeglass frame.
